BATHING APPAREL FABRIC

Thomas M. Fry, Wyomissing, Charles A. Rist, Reading,
and William F. Borda, Laureldale, Pa., assignors to
Dolfin Corporation, Shillington, Pa.

Filed Nov. 8, 1974, Ser. No. 522,054

Term of patent 14 years

Int. Cl. D5—05

U.S. Cl. D92—1 BB

The figure is a plan view of a bathing apparel fabric showing our new design. A unit of the design is indicated by dot-dash lines in the drawing. Such unit is repeated in regular succession throughout the fabric. The drawing is lined for the colors red and blue.

We claim:

The ornamental design for a bathing apparel fabric, as shown and described.
